DECORATIVE WINDOW FIXTURE

George A. Schwartz, Woodmere, N. Y.

Application March 7, 1946, Serial No. 652,677

12 Claims. (Cl. 160—38)

1

The present invention relates to a window fixture and more especially to an ornamental valance-and-drape fixture.

The use of ornamental cornices to conceal rods and other curtain and drapery fixtures has become a common feature of interior decoration. These cornices are generally made of telescoping sections to enable them to be used on windows of various widths. These have certain utility which is limited to the purposes indicated. It is often desired to frame or decorate a window along the sides as well as at the top, either to carry out preconceived decorative schemes or to conceal the plainness or unattractive lines of windows but, so far as I am aware, there is no fixture which enables this to be effectively carried out.

One of the objects of my invention is to provide for the first time, a window fixture which will give a desired valance-and-drape decorative effect.

Another object of the invention resides in the provision of a simple, relatively inexpensive window fixture which will ornament the sides of a window as well as the top thereof.

A further object of the invention is to provide a window fixture of the character described which will fit a wide variety of window sizes.

Other and further objects and advantages will be appreciated by those skilled in this art or will be apparent or pointed out hereinafter.

In the accompanying drawing:

Fig. 1 shows a window fixture embodying the present invention.

Fig. 2 is a sectional view taken on line 2—2 of Fig. 1.

Fig. 3 is a horizontal sectional view taken on line 3—3 of Fig. 1.

Fig. 4 is a view similar to Fig. 3 applied to a different type of window construction.

Fig. 5 shows a corner construction of a fixture constructed in accordance with my invention.

Fig. 6 shows a modification of Fig. 5.

Figs. 7 and 8 illustrate other forms of corner medallions.

Fig. 9 is a fragmentary view of a modified valance arrangement.

Fig. 10 is a section taken on line 10—10 of Fig. 9.

Referring first to Figs. 1, 2 and 3, it will be seen that my new window fixture comprises two valance pieces 10, a valance medallion or centerpiece 11 and two drape pieces 12 secured to or integral with the corresponding valance piece 10. These may be made of any suitable material but are preferably composed of thin plywood or other

2

composition. They may be suitably colored and may be surface-decorated with painted effects or decalcomania transfers, if desired.

Each valance piece 10 may have a mitred end 5 to cooperate with the mitred end at the top of each drape piece to which it is secured. The valance pieces are suitably mounted or secured in place in any convenient manner (such as by brackets) and are of such length that they can be used on windows of various widths without the necessity of being cut to exact size or measurement. The space between the confronting ends is covered by the ornamental medallion 11, already referred to, and which hangs over the valance 10 piece ends (see Fig. 2), due to the bar 13 and back-piece 14 which extends down almost to the top of the angle piece 15 with which the valance pieces 10 and 10b are provided. The bar 13 and back piece 14 may be secured to the medallions 11 as by nails 13a or any other suitable means. The medallion may vary greatly in size and shape and may either harmonize or contrast with the valance pieces depending on the effect to be obtained. The drape pieces 12 are each provided with an angle piece 16 similar to angle piece 15; and brackets 17 connect the angle pieces 15 and 16 with the lintel and vertical window jambs 15a respectively. Drape pieces 12 may extend to the bottom of the window as shown in full lines, to 20 the floor as shown in dotted lines or to any intermediate point. The inner edges of the valance and drape pieces are preferably scalloped or otherwise contoured in a continuous design. The outer edges are preferably plain. At spaced points the angle pieces 16 may, if desired, be provided with supporting blocks 18 for glass shelves 19 which are designed to receive plants, bric-a-brac, objets d'art or other articles.

As shown in Figs. 9 and 10, the medallion 11a 40 may be provided with a spring clip 20 by means of which it may be hooked over the adjacent ends of valance pieces 10 and as further shown in Fig. 4, the fixture may be applied to casement windows or windows of other types than the conventional 45 one represented by dash lines in Fig. 1. This is indicated on Fig. 4 by primed numerals. In the construction illustrated, the angle pieces 16' are fastened directly to the window jamb 15'.

Thus far each side of the window decoration 50 has been shown and described as made up of two mitred pieces, i. e. the valance piece 10 and the drape piece 12, but it will be understood that these pieces may be joined by a butt joint or in any other manner to produce an integral structure for 55 each side of the window opening.

If it be desired to utilize the principles of the invention, but still to use a single valance piece, then the modification illustrated in Figs. 5 to 8 may be resorted to.

In this case, the valance piece 10b is in one piece and a space exists between the ends of valance piece 10b and the upper ends of drape pieces 12b. Corner medallions 21 may be employed in a modified form of the invention as shown. The medallions are provided with a right-angled back piece 22, which constitutes an attaching connection on the rear thereof similar to back piece 14 shown in Fig. 2, and which back piece fits over the corner of the valance piece and drape pieces to cover the space between them, as shown. These corner medallions may take various shapes and designs such as the rosette 21a of Fig. 6, the shield 21b of Fig. 7 and the heart-shaped piece 21c of Fig. 8.

Here, too, the adjacent ends of the valance piece and the drape pieces are shown as mitered but they need not be so constructed since other shaped ends will produce equally good results.

The foregoing is presented as illustrative and not as limitative as other variations may be resorted to without departing from the spirit or principle thereof. The invention is rather that defined by the appended claims.

What I claim as new and desire to secure by Letters Patent, is:

1. A window fixture comprising a pair of drape pieces and a valance piece, the valance piece extending between, but terminating short of the drape pieces, and a medallion disposed over the space thereby formed between said pieces.

2. A window fixture comprising a pair of combination drape and valance sections adapted to be applied to the sides of a window frame with the free ends of the valance portions confronting each other, each section comprising a drapery portion and a valance portion secured to the upper end of the drapery portion, and a medallion disposed over the confronting ends of the valance portions and covering the space therebetween.

3. A window fixture comprising a pair of combination drape and valance sections adapted to be applied to the sides of a window frame with the free ends of the valance portions confronting each other, each section comprising a drapery portion and a valance portion secured to the upper end of the drapery portion, and a medallion disposed over the confronting ends of the valance portions and covering the space therebetween, said medallion having a hook on its back adapted to engage the valance portions.

4. A window fixture comprising a pair of combination drape and valance sections adapted to be applied to the sides of a window frame with the free ends of the valance portions confronting each other, each section comprising a drapery portion and a valance portion secured to the upper end of the drapery portion, and a medallion disposed over the confronting ends of the valance portions and covering the space therebetween, said medallion having a bar secured on its back and a back piece secured to and depending from said bar.

5. A window fixture comprising a pair of combination drape and valance sections adapted to be applied to the sides of a window frame with

the free ends of the valance portions confronting each other, each section comprising a drapery portion and a valance portion secured to the upper end of the drapery portion, and a medallion disposed over the confronting ends of the valance portions and covering the space therebetween, said medallion having a spring clip on its rearward surface.

6. A window fixture comprising a pair of combination drape and valance sections adapted to be applied to the sides of a window frame with the free ends of the valance portions confronting each other, each section comprising a drapery portion and a valance portion secured to the upper end of the drapery portion, and a medallion disposed over the confronting ends of the valance portions and covering the space therebetween, said drape and valance portions being composed of decorated plywood.

7. A window fixture comprising a pair of drape pieces having mitred upper ends, a valance piece having mitred outer edges spaced from the drape pieces and a corner medallion covering the adjacent drape and valance ends and the space therebetween.

8. A window fixture comprising a pair of drape pieces having mitred upper ends, a valance piece having mitred outer edges spaced from the drape pieces and a corner medallion covering the adjacent drape and valance ends and the space therebetween, said corner medallion being provided with a right-angled back piece by means of which it is adapted to be detachably mounted in space-covering position.

9. In combination, a window fixture as defined by claim 2 and a window jamb, the said fixture being fastened to said window jamb and being adapted to be applied to window jambs of various dimensions.

10. In combination, a window fixture as defined by claim 7 and a window jamb, the said fixture being fastened to said window jamb and being adapted to be applied to window jambs of various dimensions.

11. A combined valance and drapery window fixture adapted for attachment to window frames of various sizes and comprising a pair of spaced sections securable to a window frame and a readily removable medallion joining said sections and covering the space between said sections, said medallion having a hook on its back adapted to engage the valance portion.

12. A window fixture as set forth in claim 11, wherein each section comprises a drape portion and a valance portion integral therewith.

GEORGE A. SCHWARTZ.
